CLAIM

The ornamental design for a display screen or portion thereof with graphical user interface, as shown and described.

DESCRIPTION

FIG. 1 is a front view of a display screen or portion thereof with graphical user interface showing our new design; FIG. 2 is a front view thereof in accordance to a second embodiment;

FIG. 3 is a front view thereof in accordance to a third embodiment;

FIG. 4 is a front view thereof in accordance to a fourth embodiment;

FIG. 5 is a front view thereof in accordance to a fifth embodiment;

FIG. 6 is a front view thereof in accordance to a sixth embodiment;

FIG. 7 is a front view thereof in accordance to a seventh embodiment; and,

FIG. 8 is a front view thereof in accordance to an eighth embodiment.

The broken lines showing the mobile device is provided for the purpose of illustrating environmental structure and forms no part of the claimed design. Additionally, the broken lines showing the display screen and elements of the graphical user interface illustrate portions of the article that also form no part of the claimed design.

1 Claim, 8 Drawing Sheets
